UNITED STATES PATENT OFFICE

2,428,840

SWINGING MACHINE

George E. Estes, Drexel Hill, Pa., and Rudolf Grohskopf, Brooklyn, N.Y.

Application July 29, 1944, Serial No. 547,657

3 Claims.

(Cl. 91—42)

1

This invention relates to the art of galvanizing, plating or coating and refers more particularly to a machine employing a compound rotary and swinging motion of a container freely suspended from a hook, for the purpose of shaking off surplus zinc or other metal from galvanized articles of varying sizes.

Mass production galvanizing of small, medium size and larger articles, such as nuts, bolts, washers, household hardware, threaded rods and the like is now carried out by placing these articles into a suspended perforated container and immersing this container into the galvanizing bath. When the container is raised from the bath, the galvanized articles carry large surplus quantities of the coating metal. This surplus metal constitutes waste and it clogs some of the surfaces of the articles, such as screw threads, thus necessitating rethreading.

An object of the present invention is the provision of a machine of great simplicity having only simple rotary motion of its moving parts, yet adapted to impart a compound rotary swinging motion to a quantity of freshly galvanized articles for the purpose of shaking off surplus coating and thus providing an even and uniform layer upon the articles.

Another object is the provision of a centrifugal type machine with a basket which may be quickly and easily detached and replaced by unskilled labor, so that the machine may be used in the course of a galvanizing process for the purpose of shaking off excessive coating while it has not yet solidified.

Another object is to save a large percentage of metal wasted in a coating process and to provide articles all the surfaces of which carry a uniform even coating, thereby eliminating the necessity of rethreading articles which are provided with screw threads.

Other objects will become apparent from the following specification.

In accomplishing the objects of the present invention it was found desirable to provide a body in the nature of a container and a vertical shaft above the body terminating in a hook at about the top of the body. The perforated metal basket containing freshly galvanized articles is quickly removed from the galvanizing bath and suspended from this hook by a rigid, pivoted strap handle.

On revolution of the shaft the basket not only rotates with it but swings outwardly from the axis of the shaft. Surplus coating metal carried by the articles in the basket is thus shaken off

2

and ejected through the perforations in the basket upon the inner walls of the container-like body. The metal is shaped off these walls and is ready then for repeated use.

The invention will appear more clearly from the following detailed description when taken in connection with the accompanying drawings showing, by way of example a preferred embodiment of the inventive idea.

10 In the drawings:

Figure 1 is a front elevation of the machine.

Figure 2 is a side elevation partially in section to show the suspended perforated metal basket.

Figure 3 is a horizontal section along the line 15 3—3 of Figure 1.

The machine includes a body 4 (Fig. 1), with a door 5. The body 4 is to enclose the basket 6 (Fig. 2), and supports the shaft frame and brake. The shaft frame includes brackets or side legs 20 7 and 8, an upper main bearing housing 9 between them (the three members having roughly the form of half an oval flattened at the top, or an inverted U), and a cross member 10, connecting the side legs 7 and 8, about halfway up and comprising the lower main bearing housing 11.

Also part of the shaft frame is the motor supporting leg 12 (Fig. 2), extending sidewise of the upper housing 9, and downward to the body and bracing the members 7 and 8 against belt 30 pull. A motor 13 is mounted in vertical position on the leg 12, its feet being bolted to feet 14 and 15 formed on leg 12.

The shaft 16, terminating at its lower end in a hook 17, is mounted in the housings 9 and 11, and carries a pulley 18, driven by a belt 19, which is driven by pulley 20 on the motor.

A brake shoe 21 is pivoted to an arm 22, which is keyed upon a shaft 26, mounted on standard 27, on the left top side of the body 40 (looking in the direction of Figure 1), and a bracket 23, which is mounted on leg 12 by bolting its foot 24 to a foot 25 formed on leg 12. Arm 22 is also keyed upon the shaft 26 and is pivotally connected by rod 28 to angle arm 29 which is 45 pivoted to the outside lower portion of the body below standard 27. Arm 29 is pivotally connected by rod 30 to angle arm 31, which is pivoted to the left side of the body at the bottom and near the front (Fig. 1) and bears a pedal surface 32 at its outer end. This assembly is thus adapted to transform pedal pressure into pressure of brake shoe 21 against pulley 18. An extension coil spring 33 connects brake shoe 21 to leg 12, and is adapted to disengage brake shoe 21 from pulley 50 18 when pedal pressure is relieved.

55

Figure 3 shows a semi cylindrical shield or inner wall 34, extending the height and width of the body interior and located in the rear half thereof. The body top consists of covers 35 of light sheet steel, which extend from the back of the body to a line about even with the point of the basket nearest the front, and have a U-shaped opening over the basket, slightly larger than the basket and with its open end to the front. Rigidity is imparted to this cover by two angle irons 36 and 37 bolted to it and to the body frame. A smaller cover 38 extends from cover 35 to the front and is cut out substantially along the circle partly described by the shield 34, forming an opening 39 which includes the U in cover 35. A start-stop motor control switch 41, is located on the front of the body at the top left corner.

The device is operated as follows:

The perforated basket 6 which is filled with galvanized articles, is quickly lifted by a pulley or the like from the galvanizing bath and then lowered through the opening 39 and hung upon the hook 17. Then the motor is started rotating shaft 16 and causing the basket 6 to rotate and also to swing outwardly from the axis of shaft 16. This compound rotation and swinging causes the excess particles of zinc or other coating metal, which are still in liquid or semi-liquid state and are located upon various surfaces of the articles within the basket 6, to be ejected through the perforations in the side and bottom of the basket.

The shield 34 collects these escaped particles which solidify thereon. Then they can be scraped off or otherwise removed by any suitable means.

The progress of the shaking off process may be observed through hole 39 at all times.

The machine is stopped by shutting off power to the motor and a quick stop is provided by pressure on the pedal 32.

The advantage of this procedure is that from 40% to 60% of zinc used in galvanizing is saved and that the articles receive a uniform even coating. The elimination of surplus coating makes it unnecessary to rethread articles provided with screw threads.

It is apparent that the illustration shown above has been given solely by way of illustration and not by way of limitation, and that the above described machine is subject to wide variation and modification. All of such variations and modifications are to be included within the scope of the present invention.

What is claimed is:

1. A machine for shaking off surplus coating from coated articles in a container, said machine comprising a stationary body, a vertical shaft above said body, means adapted to support said shaft, a pulley on said shaft, means adapted to rotate said shaft and pulley, brake means for said pulley, said brake means comprising, a bracket, a rock shaft rotatably supported thereon, an arm secured to said rock shaft, a brake

shoe adapted to engage said pulley carried by said arm, spring means exerting a tension on said arm for normally maintaining said shoe out of engagement with the said pulley, and foot operated means operatively connected to said brake shaft for partially rotating same to bring the brake shoe in braking contact with the said pulley and means for suspending said container in said body from said shaft.

2. A machine for shaking off surplus coating from coated articles in a container, said machine comprising a hollow stationary body adapted to receive said container, a cover upon said body and having an opening formed therein through which said container may be lowered into said body, a shaft frame having the form of an inverted U and carried by said body, a vertical shaft carried by said shaft frame above said body and having a hook integral therewith upon its lower end, said hook being located substantially within said opening and being adapted to carry said container, a pulley keyed upon said shaft, a leg between said body and said frame at substantially right angles to the latter, a motor carried by leg, means operatively connecting said motor with said pulley, braking means connected with said leg and adapted to engage said pulley, and a wall removably secured to said body for receiving particles of surplus coating.

3. A machine for shaking off surplus coating from coated articles in a container, said machine comprising a stationary body, a vertical shaft above said body, means adapted to support said shaft, a pulley on said shaft, means adapted to rotate said shaft and pulley, a bracket, a rock shaft rotatable in said bracket, an arm secured to said rock shaft, a brake shoe carried by said arm and adapted to engage said pulley, spring means exerting a tension on said arm for normally maintaining said arm out of contact with the said pulley, a second arm secured to said rock shaft, a bell crank lever pivotally mounted near the bottom of the frame, a link pivotally connected to the said second arm and to one arm of the bell crank lever, a pivotally mounted foot lever, and a link connecting said foot lever to the other bell crank arm as and for the purpose specified.

GEORGE R. ESTES.
